UNITED STATES PATENT OFFICE.

JOHN G. SNYDER, OF GREEN ISLAND, NEW YORK.

MANIFOLD FOR GAS ENGINES.

1,413,804.

Specification of Letters Patent. Patented Apr. 25, 1922.

Application filed July 19, 1920. Serial No. 397,448.

To all whom it may concern:

Be it known that I, JOHN G. SNYDER, a citizen of the United States, and a resident of Green Island, county of Albany, and 5 State of New York, have made certain new and useful Improvements in Manifolds for Gas Engines, of which the following is a full and complete specification.

It is customary by means of a carbureting 10 device to produce a gaseous, or mixed gaseous and liquid fuel in a stream to be delivered to the several explosion chambers of a gas engine. Dependent upon the speed of the engine and the existing temperature 15 great variation is frequently found in the quality of fuel which is delivered to the respective cylinders. It is also obvious that the difference in the length of travel to the various cylinders further effects the uniformity of the fuel stream. To properly 20 deliver to each of the cylinders in a gas engine a stream of gaseous fuel of uniform character is an important factor in the maintenance of good gas engine operation. De- 25 pending upon various temperature changes in the air passing the carburetor and the surrounding machine parts there is a corresponding variation in the degree to which the liquid fuel is vaporized. It is frequently 30 found that the fuel is entrained in a current of air and may even arrive in the explosion cylinders in the form of small globules. Under these circumstances there is a consequent loss in motive force.

35 It is an object of my invention to blend the vaporized fuel thoroughly with the air stream as it passes into the various cylinders of the engine and thus promote the operation of the latter.

40 It is a further object of my invention to insure uniformity in the delivery of the gaseous mixture to the cylinders avoiding all possibility of feeding a lean mixture to one cylinder and a rich mixture to another.

45 It is also a further object of my invention to insure a perfect vaporization of such portions of the fuel as may pass the carburetor without volatilization. As will be evident from the description this is accomplished 50 both by mechanical means and through heat transference.

Other objects of my invention will be evident from the following description taken in conjunction with the drawings in which:—

55 Fig. 1 shows a longitudinal cross section

of a manifold embodying one form of my invention and taken along the line 1—1 of Fig. 2.

Fig. 2 is a transverse cross-section through 2—2 of Fig. 1. 60

As illustrated in the drawings one form of my invention consists in the casting 3 which provides suitable chambers and passage-ways for exhaust, intake, and mixing of the fuel. 65

Ports 4 pass through one side of the casting and connect with the exhaust ports of the respective cylinder heads, in the present instance the casting being shown as adapted for a typical four-cycle engine. The ports 70 4 deliver the exhaust gases to the channels 5 which have their prolongation in the member 6 internally screw-threaded for connection with the customary exhaust tubing. In line with the centres of the ports 4 are the 75 inlet ports 7 which are branched, not shown, to connect with the inlet ports or valves of the gas engine. It is to be understood that each port 7 serves two cylinders. The ports 7 are connected by means of the passage 80 ways 8 to a chamber 9 extending the full length of the casting 3. The ends of the chamber 9 are formed by the pipe plugs 10 and 11 which are screw-threaded into the casting. In some instances it is found that 85 one end only of the casting need carry an opening with the pipe plug.

Separated by a thin wall 12 from the exhaust passage-ways 5 is an extended vaporizing recess 13. This recess 13 is substantially 90 as long as the distance between the ports 7, and the casting is molded or cut-away on the exhaust or lower side thereof to provide a small partition which is advantageous as will hereinafter appear. An inlet 13' is disposed above the center of the recess 13 and connects the mid-portion of the chamber 9 with the carburetor of the engine. The top wall 14 of the vaporizing recess is slotted 95 as at 15 throughout its entire length and this slot at its ends becomes a corresponding groove 16 in the side walls 17 and 18 of the duct. This slot connects the vaporizing recess 13 with the longitudinal chamber 9. 100

Disposed throughout the length of the chamber 9, co-axial therewith, and substantially in contact with its inner wall is a mixing device 19. This mixing device consists of a blade twisted into a helicoidal form for the greater part of its length. This 110

helicoidal form consists of two helices 20 and 21 merging at the centre as at 22 and having opposite pitches extending the complete width of the chamber 9 and aggregating the 5 length of the slot 14 of the vaporizing recess. The helices, at this central meeting point, merge and may be said to have a neutral pitch since they serve to receive the gas and unvolatilized fuel coming from the inlet 10 13' and divide the stream equally part going in each direction. Beyond the helices 20 and 21 are the rod ends 23 and 24.

A thin metal bar 25 is provided the length of the slot 14 and the groove 16, and of a 15 width sufficient to occupy the width of the groove. This bar is cut away on one side for a length equal to that of the slot 14 and a blade 26 is set up from the corresponding side at an inclination to the radius of the adjacent helix. This blade 26 intersects the helices in a line parallel to the axis of the latter. The helices may be cut away to permit the use of a blade of continuous edge or conversely the blade may be cut away at regular 20 intervals to permit the passage of a continuous helix.

In either event the blade and the mixing member 19 are assembled prior to installing in the manifold casting. The pipe plugs 10 30 and 11 are of sufficient diameter to permit the insertion of the assembled members 19 and 25, the latter to seat themselves in the chamber 9 being properly spaced from the ends of the pipe plugs 10 and 11 by the rod 35 ends 23 and 24. The helices are in substantial contact with the inner walls of the chamber 9 and the bar 25 rests in the groove 16.

In the form as shown in the drawing, the stream entering through the inlet 13' meets 40 the divergent helices and is divided, forming two streams travelling toward opposite ends of the member 19. As these streams follow their spiral courses, the centrifugal effect is such as to cause the liquid fuel particles to 45 approach the sides of the chamber 9. As the particles reach the lower point of travel and the inwardly extending blade 26, they are caught and deflected by the latter downward through the slot 14 and into the recess 13. 50 This recess is heated by the passage of the exhaust gases in contact with the lower wall 12 and the entering particles of fuel are therefore quickly vaporized. As the fuel vaporizes, it expands and travels upward 55 through the slot 14, mingling with the fuel streams as they pass through the chamber 9.

From the above description it will be evident that a fuel stream from a carburetor will be effected in the following manner. As 60 the stream enters through inlet 13' into the chamber 9, it is divided into two equal streams toward the opposite ports 7. The spiral path carries the liquid fuel particles centrifugally and thus serves to strain or 65 separate the stream of all but vaporized com-

ponents. During this step it will be apparent that the fuel is kept out of contact with heated surfaces and its temperature remains low. The globules of fuel, segregated by centrifugal force and under the influence of 70 gravity, are intercepted by the blade 26 and pass down beyond the bar 25, into the recess 13. Due to the proximity of the latter recess to the exhaust gas passage ways, the liquid fuel is caught in the recess and vaporized. 75 There results a consequent expansion of the fuel as vapor, and the increased volume produces a current upward through the slot 14 in contact with the descending liquid particles. The vaporized fuel now blends with 80 the fuel stream passing the helices and is thoroughly mixed. The flow upward through the slot 14 is at an increased velocity due to the volatilization and expansion of the fuel under heat in the recess 13 and this upward 85 flow impinges against the blade 26 with considerable violence. This is an added factor in promoting the mixing of the material in the chamber 9.

It is remarked that the blade 26 when intercepting the entrained globules will also deflect a small quantity of the gaseous stream downward into the recess. This quantity of gas has a sweeping or scavenging effect in the recess and aids in the return to the chamber 95 9, of the vaporized fuel. It will be apparent from Fig. 1 that the blade 26 is subdivided into a number of parts by its intersections with the helices 20 and 21. By tracing the current flow from the inlet 13' it will be 100 found that there is little tendency for the fluid to cross the center of the blade 26 into the chamber 13 while the centrifugal force developed toward the outer ends of the helices brings the liquid particles and part 105 of the gaseous fluid into the intercepting influence of the blade. There is thus produced what has been above termed a scavenging effect whereby eddy-currents flow into the ends of the chamber 13 and outward through 110 its central area. It is further noteworthy that the fuel stream from the carburetor to the inlet ports 7 is not subjected as an entirely to heating influence, but on the contrary a separation is effected of the gaseous 115 portion from the heavier and unvaporized particles and the latter only are heated. In this manner the volumetric efficiency of the fuel stream is maintained unimpaired.

During the passage through the slot 14 120 and the mixer the fuel mixture is thoroughly vaporized and homogenized. In passing through the helices the charge is kept uniform in the two directions which it takes through the mixer. It will be evident that 125 the fuel charge is therefore delivered to the ports 7 in uniform streams and that the helices serve the further object of preventing back pressure or eddy currents.

The particular embodiment of my inven- 130

tion shown, is of course, susceptible of considerable variation without departing from the spirit of my invention, and it is to be understood that many changes may be made by 5 those skilled in the art, within the scope of the invention as defined in the appended claims.

I claim:

1. A manifold having an inlet duct, one or 10 more passageways adapted to convey fuel to the inlet valves of a gas engine, a mixer interposed between said duct and a passageway, said mixer including means to separate out unvaporized fuel intercepting means for 15 said unvaporized fuel, and a vaporizing recess for receiving said unvaporized fuel.
2. A manifold having an inlet duct, one or more passageways adapted to convey fuel to the inlet valves of a gas engine, a helicoidal 20 mixer interposed between said duct and a passageway, and intercepting means contiguous to and projecting within the periphery of said mixer.
3. A manifold having an inlet duct, one or 25 more passageways adapted to convey the fuel to the inlet valves of a gas engine, a mixer interposed between said duct and a passageway, and a blade within the passageway inclined to the fuel stream flowing 30 through the mixer.
4. A manifold having an inlet duct, a plurality of passageways adapted to convey fuel to the inlet valves of a gas engine, mixers, one of said mixers being interposed between 35 said duct and each passageway, said mixers segregating unvaporized fuel, intercepting means for said unvaporized fuel, said manifold having a vaporizing recess for receiving said unvaporized fuel and returning 40 it to the passageways in the form of vapor.
5. A manifold having an inlet duct, a passageway adapted to convey fuel to the inlet

valves of a gas engine, means interposed between said duct and the passageway for 45 mixing air and gaseous fuel and for segregating unvaporized fuel, intercepting means for said unvaporized fuel, said manifold having a vaporizing recess to receive the intercepted fuel. 50

6. A manifold having an inlet duct, a plurality of passageways adapted to convey fuel to the inlet valves of a gas engine, helicoidal mixers, one of said mixers being interposed between said duct and each passageway, and intercepting means projecting 55 within the periphery of the mixers.

7. A manifold having a plurality of passageways to the inlet valves of a gas engine, including a mixing chamber connecting said 60 passageways, said manifold having a recess underlying the said chamber connecting therewith and in close relationship to the exhaust passages of the gas engine.

8. A manifold having a plurality of passageways to the inlet valves of a gas engine, including a mixing chamber connecting said 65 passageways, said manifold having a recess underlying the said chamber connecting therewith and in close relationship to the exhaust 70 passages of the gas engine and an intercepting member extending up from the recess into the mixing chamber.

9. A mixing device for a manifold, comprising a helicoidal member, a bar, and a 75 blade on said bar intersecting the helix of the member.

10. A mixing device for a manifold, comprising a helicoidal member having helices of opposite pitch and extending from the 80 center of the member, a bar parallel with the axis of the member, a blade on said bar and intersecting the helices.

In testimony whereof, I have hereunto affixed my signature.

JOHN G. SNYDER.
